UNITED STATES PATENT OFFICE.

PAUL CARL JEAN PAFFRATH, OF ALtenburg, GERMANY, ASSIGNOR OF TWO-THIRDS
TO RICHARD POCHWADT AND ARNO GUNZEL, BOTH OF ALtenburg, GERMANY.

AUXILIARY AIR INLET FOR INTERNAL-COMBUSTION ENGINES.

Application filed May 25, 1922. Serial No. 563,741.

To all whom it may concern:

Be it known that I, PAUL CARL JEAN PAFFRATH, citizen of Germany, residing at Altenburg, Sachsen-Altenburg, Germany, Langgasse 21, have invented certain new and useful Improvements in an Auxiliary Air Inlet for Internal-Combustion Engines, of which the following is a specification.

My invention relates to improvements in internal combustion engines, and more particularly in engines, of the type in which means are provided for admitting secondary air to the combustible mixture, and in which the valve controlling the supply of secondary air is controlled by the suction transmitted from the cylinder or cylinders to the suction pipe. The object of the improvements is to provide means of this class which are simple in construction and reliable in operation. With this object in view my invention consists in providing, within a chamber communicating with the suction pipe, a piston formed with a tubular portion extending into position for discharging secondary air into the suction pipe, and providing at its inlet end a valve body adapted to be set relatively to a valve seat according to the action of the suction on the piston.

In order that my invention be more clearly understood an example embodying the same has been shown in the accompanying drawing, in which the same reference characters have been used in all the views to indicate corresponding parts. In said drawing—

Fig. 1, is a sectional view showing a part of the suction pipe of an internal combustion engine,

Fig. 2, is a horizontal section taken on the line 2—2 of Fig. 1, and

Fig. 3, is a horizontal section taken on the line 3—3 of Fig. 1.

In the example shown in the figures to the suction pipe *c* of the internal combustion engine the reduced part *b* of the cylinder *a* is screwed, which is provided with a head *h* formed with holes *g* and a valve seat *i*. Within the cylinder an annular piston *d* is mounted which carries a pipe *e* extending into the suction pipe and formed with diverging apertures *f* through which secondary air is distributed and discharged into the suction pipe. At the side opposite to the pipe *e* the piston *d* is in the form of a valve body *i'*, operating with the valve seat *i*. Between

the pipe *e* and the reduced portion *b* of the cylinder an annular passage *b'* is provided through which the chamber *o* of the cylinder located above the piston *d* communicates with the suction pipe, so that the piston *d* is acted upon by the vacuum within the suction pipe permitting the valve *i'* to be raised from its seat by the pressure of the outer air transmitted to the lower side of the piston through the holes *g*. Between the bottom face of the head *h* and a disk *n* adjustable on a screw-threaded spindle *l* secured to the top end of the pipe *e* a spring *m* is interposed, which has the tendency to force the valve *i'* on its seat *i* against the action of the atmospheric pressure and the vacuum acting on the piston *d*. Preferably the pipe *e* is formed with ribs *k* by means of which it is guided within the reduced part *b* of the cylinder *a*.

The operation of the apparatus is as follows: When starting the engine a vacuum is produced within the suction pipe *c* which is transmitted through the annular passage *b'* to the chamber *o*, so that the piston *d* is forced upwards by the pressure of the outer air against the pressure of the spring *m*, and the valve *i'* is unseated. Therefore, a certain amount of secondary air is admitted through the holes *g* and the pipe *e*, which is discharged in a state of fine distribution into the combustible mixture flowing through the suction pipe *c*. The elevation of the valve and the volume of secondary air supplied to the combustible mixture depend on the vacuum within the suction pipe *c* and on the number of revolutions of the engine. The elevation of the valve is regulated according to the requirements of the engine by setting the disk *n* on the spindle *l*. The operation of the piston *d* is not interfered with by the flow of the secondary air through the same.

While in describing the invention reference has been made to a particular example embodying the same, I wish it to be understood that my invention is not limited to the construction shown in the figures, and that various changes may be made in the general arrangement of the apparatus and the construction of its parts without departing from the invention.

I claim:

1. The combination with the intake conduit of an internal combustion engine, of a device for supplying auxiliary air to the

2
combustible mixture flowing therethrough, comprising a cylinder attached to said conduit and opening therein, a piston in said cylinder, an elongated hollow member projecting from the suction face of said piston into said conduit, said hollow member being provided with a plurality of perforations through that part which projects into said conduit, said piston having a central opening communicating with the interior of said member and terminating at the atmospheric side thereof in an annular valve face, a perforated cap on said cylinder having a central boss forming a seat for said valve face, and yieldable means for holding said valve parts in closing relation.

2. The combination with the intake conduit of an internal combustion engine, of a device for supplying auxiliary air to the combustible mixture flowing therethrough, comprising a cylinder attached to said conduit and communicating therewith, a piston in said cylinder, an elongated hollow member projecting from the suction side of said piston into said conduit, said hollow member being provided with a number of small openings through that part which projects into said conduit, said piston having a central opening communicating with the interior of said hollow member and terminating at the atmospheric side thereof in a valve face, a seat for said valve face at-

tached to said cylinder, and yieldable means for holding said valve parts in closed relation.

3. The combination with the intake conduit of an internal combustion engine, of a device for supplying auxiliary air to the combustible mixture flowing therethrough, comprising a cylinder having a reduced neck attached to said conduit and opening therein, a piston in said cylinder formed with a central hollow member projecting through said neck into said conduit and having a plurality of small openings in that part which projects in said conduit, said member forming with said neck an annular passage between said conduit and cylinder, the bore of said hollow member extending through said piston and terminating in an annular valve face, a perforated cap on said cylinder having a central boss forming a seat for said valve face, a stem attached to the upper end of said hollow member passing axially therethrough and through said boss and cylinder cap, an abutment on said stem, and a coil spring between said abutment and cylinder cap.
